UNITED STATES PATENT OFFICE.

JOE S. MCKIBBON, OF CULLEOKA, TENNESSEE.

WRENCH.

Application filed March 29, 1928. Serial No. 265,800.

This invention relates to improvements in wrenches, and more particularly bears upon a modified construction of the wrench described in my Patent 1,423,499, granted July 5 18, 1922.

One of the objects of this invention is to provide a modified adjusting device for controlling the separation of the wrench jaws.

Another object of this invention is to provide means for automatically moving the jaws relative to each other into the projected position.

Other objects of the invention will appear in the course of the following specification and claims, taken in conjunction with the accompanying drawings, which represent by way of illustration, one form of construction of a wrench according to this invention.

In the drawings:

20 Figure 1 is a side elevation of the improved wrench, with portions broken away and sectioned to show the relationship of the respective parts.

25 Fig. 2 is a perspective view of the adjusting ferrule.

Fig. 3 is a corresponding sectional view of one of the adjusting screws.

Fig. 4 is a diametral section through the adjusting ferrule or spindle.

30 Fig. 5 is a perspective view of the connecting link.

In these drawings, the illustrated form of the invention has a stationary jaw 10 and a movable jaw 11, each having rearwardly extending shanks. The shank of the stationary jaw at its rear end has a handle extension 12. A connecting link 13 is formed of two face plates (Fig. 5) which are joined and spaced by the pivot pins 14, so that the shanks of 40 the movable and stationary jaws 10, 11 are received between the face plates 13. Each of the shanks has a respective notch 15, 16 on the rear end, i. e., the end opposite the engaging surfaces 29, to receive the respective 45 pivot pins 14. The jaws are permitted a limited relative lengthwise movement by the connecting link 13 which forms a rolling hinge connection. A flat blade spring 17 is secured to the stationary jaw 10 and bears 50 against the movable jaw 11 to force the engaging surfaces 29 apart.

Each of the jaws is provided with a hole or cavity 18 which diverges inwardly or toward the adjacent faces of the jaws, and terminates at the outer face of the respective jaw in a widened seat 19 to receive the head 55

20 of an adjusting screw 21. The head 20 is formed oblong in a plane at right angles to the axis of the screw thread, and the seats 19 are correspondingly shaped, so that the 60 corresponding screw 21 may rock in the plane of the jaws but cannot rotate about its axis relative thereto.

As shown in Fig. 3, the heads are formed so that the cross section taken in any plane 65 parallel to the line of the jaws, i. e., a plane of movement of the corresponding parts of the screws 21 and the threaded spindle sleeve 22, is preferably a circular arc, so that the head can rock easily in the respective jaw 70 without binding, while the cross sections at a right angle to these are oblong to prevent the head from rotating in its seat about the axis of the screw.

A sleeve 22 having internally threaded 75 holes at its ends receives the two oppositely threaded screws 21; and is provided at its central portion with a thumb disk or nut 23 for adjustment. The sleeve 22 and screws 21 thus form an adjusting device to 80 regulate the distance between the engaging surfaces of the jaws.

The handle end 12 of the stationary jaw is provided with a lug 24 which fits against a surface 25 formed on the movable jaw, 85 whereby to limit a normal relative separation of the jaws.

The shank end 30 of the movable jaw 11 is formed to enter a recess 31 located in the shank of the fixed jaw 10 adjacent the 90 handle 12, and by its abutting relationship therein to be held thereby against a farther movement of the movable jaw 11 in the direction toward the left in Fig. 1, thus limiting the movement of the adjusting device 95 and the connecting link 13 under such conditions. This end of the movable jaw 11 is formed with a cavity 28, and the bottom of the recess in the stationary jaw is formed with a similar cavity 27 which serve to receive the ends of a coil spring 26 which tends to normally force the movable jaw toward the right in Fig. 1.

It will be seen that the adjusting device comprising the sleeve 22 and the screw 21, when located at an intermediate position, that is, at substantially a right angle with respect to the jaws, will permit the surfaces 29 of the jaws to be at a maximum distance apart for the particular setting of the adjusting device. When the movable jaw 11 is moved toward the left against the action

of the spring 26, as by engagement about a nut, this adjusting device will be moved to an angle other than a right angle, and thus the jaw surfaces 29 are brought closer together than the maximum separation determined by the adjusting device. The jaw 11 is limited in its movement toward the left by the engagement of the shank end of the movable jaw with the stop formed by the 10 projecting lug 24, that is, when the portion 30 becomes seated in the recess 31. When the movable jaw 11 is moved toward the right from the intermediate position by the action of spring 26, the adjusting device 15 will likewise rock to an angle other than a right angle with respect to the jaws, but this time in the opposite direction, thus bringing the jaws closer together again.

It is preferred to form the engaging surfaces 29 of both jaws 10 and 11 with biting teeth.

The operation of the device is as follows: The thumb nut or disk 23 is rotated by the fingers, thus rotating the spindle 22 with 25 respect to the screws 21 and thus causing the heads 20 of the latter to move closer together or further apart, according to the direction of the rotation of the thumb nut 23. The jaws 10, 11 are thus brought 30 closer together by the pull of the screws and sleeve, or are moved apart by the action of the spring 17, until the jaw surfaces 29 are at the proper distance to engage the article. It will be noted that the tapered 35 shape of the cavities 18 permits the jaws, sleeve and screws to move freely. During this preliminary operation, the spring 26 has maintained the movable jaw 11 in a right hand or projected position with respect to 40 the showing of Fig. 1, the connecting link 13 rocking to permit this until the rearward end of the movable jaw 11 is stopped by its relative downward movement and engagement on the corresponding portion of the 45 stationary jaw 10.

If the device is now placed on a nut, a pipe, etc., and the handle 12 forced upward in Fig. 1, the movable jaw will tend to move toward the left in Fig. 1 toward the 50 retracted position, against the action of the spring 26; and this movement, by the change of angle of the adjusting device with respect to the jaws, will permit a slightly greater separation of the jaws so that they slip 55 easily onto the nut or pipe. The connecting link 13 permits this longitudinal movement until the portion 30 is seated in the recess 31; the link 13 permits a slight upward movement of the rear end of the movable 60 jaw 11 which during the latter part of this movement operates, in conjunction with the relative longitudinal movement of the jaws and the further change of angle of the adjusting device, to bring the jaw surfaces 29 closer together whereby the nut or pipe is

gripped tightly for turning. A reverse movement of the handle 12 will permit the spring 26 to move the movable jaw so that the adjusting device passes toward the intermediate position, and the greater separation 70 of the jaws thus effected will permit freeing the device from the nut or pipe.

If the device is placed around a nut, a pipe, etc., and the handle is moved downward in Fig. 1, the movable jaw 11, being 75 moved longitudinally toward the right relative to the fixed jaw 10 by the spring 26, will cause the adjusting device to move beyond its intermediate position whereby to cause the jaws to closely engage the nut, etc., and the wrench may now be employed for turning the nut in the opposite direction, i. e., counterclockwise in Fig. 1. It will be noted that this possibility of operation in either direction is afforded, so that 80 the wrench may be employed for rotating the nut on or off without turning the wrench upside down in passing from one method of operation to the other. Since the spring 17 maintains the separation of the jaws at all 85 times, the pivot pins 14 and the heads 20 of the screws 21 determine the separation of the jaw surfaces 29.

It is preferred to locate the handle extension 12 with respect to the stationary jaw and shank so that it is substantially 90 symmetrical with respect to both jaws when closed, so that a symmetrical appearance is given to the whole.

It is of course immaterial whether the 100 work engaging faces of the jaws are inclined to their shanks, as shown in the drawings, or otherwise arranged; or whether the faces are parallel with each other or otherwise arranged. It will be understood that the 105 wrench can be used either side up; that is, with the movable jaw on top as illustrated, or with the movable jaw on the underside.

It is obvious that the invention is not 110 limited to the illustrated form of construction; but that it may be applied in many ways within the scope of the appended claims.

What is claimed as new is:

1. A wrench comprising stationary and 115 movable jaws and shanks, a connecting link pivoted to said shanks and permitting relative lengthwise movement of the jaws between projected and retracted positions, a spring acting between the jaws and shanks 120 to move them to the longitudinally projected position, and means to regulate the distance between the engaging surfaces of the jaws.

2. A wrench having stationary and 125 movable jaws, means connecting the jaws and permitting relative lengthwise movement, and holding the engaging surfaces thereof at regulated distances, a spring engaging and forcing said jaws apart, said means including an adjusting device to determine the 130

maximum separation of the jaws, and a spring cooperating with said jaws to cause a relative lengthwise movement thereof.

3. A wrench comprising stationary and movable jaws, a connecting link connecting the jaws at one end and permitting a relative lengthwise movement, resilient means for moving the movable jaw lengthwise of the stationary jaw, said jaws having alined 10 cavities adjacent the engaging surfaces extending through the respective jaw substantially perpendicular to the length of the jaw, and terminating at the outer side of the jaw in an elongated seat, threaded members 15 having elongated heads engaging said seats, and a threaded member cooperating with the aforesaid threaded members to regulate the distance between said jaws whereby to adjust the wrench for different articles.

20 4. A wrench having stationary and movable jaws with alined tapered holes therein, a rolling hinge connection between the rear ends of the jaws, inwardly directed screws having enlarged heads and located in said 25 holes, and an internally threaded spindle positioned within and between said jaws to cooperate with said screws to limit the separation of said jaws and having a turning means located between said jaws whereby 30 it may be rotated, the enlarged heads of said screws being oblong and having curved inwardly directed surfaces and being entirely received in similarly shaped enlargements of the outer ends of said holes whereby to prevent 35 rotation of the screws about their respective axes but permitting them to rock relative to the respective jaw and to leave the outer faces of the jaws unobstructed,

said screws and sleeve member being adapted to rock in said holes whereby to permit the 40 relative lengthwise movement of said jaws.

5. A wrench as set forth in claim 4, in which a spring is provided to force the movable jaw into a longitudinally projected position with respect to said fixed jaw. 45

6. A wrench having stationary and movable jaws, means connecting the rear ends of the jaws to permit relative lengthwise movement thereof, interengaging abutting means on said jaws to limit their relative 50 longitudinal movement in one direction, and an adjusting device connecting said jaws to determine the maximum separation of said jaws, said adjusting device permitting a relative lengthwise movement of said jaws and 55 operating at the ends of said movement in either direction to cause the jaws to move closer together.

7. A wrench having stationary and movable jaws with alined tapered holes therein, 60 adjustment means connecting said jaws and permitting a relative lengthwise movement thereof while fixing a maximum separation of said jaws, said means comprising devices rockable with said jaws so that in an intermediate position the jaws are at a maximum separation, while in their end positions of relative longitudinal movement the jaws are at a lesser separation, means to connect the rear ends of said jaws to permit such 70 longitudinal movement, and interengaging abutting parts on said fixed and movable jaws to limit the relative longitudinal movement of said jaws in one direction. 65

In testimony whereof, I affix my signature.
JOE S. McKIBBON.
